CLAIM

The ornamental design for an electric lantern, as shown and described.

DESCRIPTION

FIG. 1 is a perspective view of an electric lantern of the claimed invention, having a translucent globe, as indicated by diagonal shading.

FIG. 2 is a front side elevation view of the electric lantern of FIG. 1.

FIG. 3 is a back side elevation view of the electric lantern of FIG. 1.

FIG. 4 is a left side elevation view of the electric lantern of FIG. 1.

FIG. 5 is a right side elevation view of the electric lantern of FIG. 1.

FIG. 6 is a top plan view of the electric lantern of FIG. 1; and,

FIG. 7 is a bottom plan view of the electric lantern of FIG. 1.

The broken lines shown in the drawings represent unclaimed portions of the article and form no part of the claim.
